J. P. BURTON,

LIFTING BUOY,

APPLICATION FILED DEC. 3, 1918.

1,299,121.

Patented Apr. 1, 1919.

UNITED STATES PATENT OFFICE.

JOHN PERCIVAL BURTON, OF OAKVILLE, ONTARIO, CANADA.

LIFTING-BUOY.

1,299,121.

Specification of Letters Patent.

Patented Apr. 1, 1919.

Application filed December 3, 1918. Serial No. 265,124.

To all whom it may concern:

Be it known that I, JOHN PERCIVAL BURTON, of the town of Oakville, in the county of Halton, in the Province of Ontario, Canada, have invented certain new and useful Improvements in Lifting-Buoys, of which the following is the specification.

My invention relates to improvements in lifting buoys and the object of the invention is to devise a lifting buoy which may be operated entirely from the interior when the buoy is submerged, dispensing with the necessity of employing a diver for attaching the buoy to the vessel to be raised and at the same time providing means for increasing the buoyancy to the required extent and for steering the device in the direction required and it consists essentially of the following arrangement and construction of parts as hereinafter more particularly explained.

Figure 1, is a vertical section through my lifting buoy showing it in the operative position.

Fig. 2, is a sectional plan view on line 25 *x—y* Fig. 1, drawn on a smaller scale.

In the drawings like characters of reference indicate corresponding parts in the various figures.

1 indicates the outer casing of a buoy, the upper portion of which is spherical in form, the lower portion 1^x tapering down from the spherical upper portion and terminating in a rounded portion 1'. The upper portion 1 may be divided into two portions 1² and 1³ at 1⁴, the parts being connected together by interiorly extending annular flanges 1⁵ and 1⁶ bolted together, the joint being so packed as to render the device air and water tight.

2 indicates an inner casing, the lower portions 2^x and 2' of which conform to the general shape of the outer casing 1, the walls of the inner casing being spaced apart from the walls of the outer casing and connected thereto by a suitable bracing structure 3.

The upper part of the portion 2^x is segmental spherical in form and of such a curve as to form a space between the upper portions of the outer and inner casings, having its greatest depth in the center, the space gradually tapering off toward its outer edge. The upper part of the casing 2 may also be divided into two portions 2² and 2³ connected together by the opposing flanges 2⁴ and 2⁵ suitably bolted together and packed to form an air tight joint. The lower end 2⁰ of the

portion 2' of the casing 2 is of segmental spherical form, the arc of which is of greater radius than the round lower portion 1' of the outer casing 1 thereby forming an intervening space between the lower ends of the outer and inner casings which has a greater depth at the center than at the sides. Within this space which I designate 2⁶ I form a cross partition 2⁷, the portion of the outer casing below the partition 2⁷ being provided with suitable openings 2⁸ allowing the free entrance of water thereinto, such space below the partition 2⁷ forming a propeller chamber. The upper portions of the outer and inner casings are provided with orifices 1⁷ and 2⁹ connected together by the cylindrical portion 2¹⁰ forming a manhole through which the occupants of the lifting buoy pass. The upper end of the cylinder 2¹⁰ is provided with a hinged cover 2¹¹. 2¹² indicates a link rod connecting the cover 2¹¹ with an operating lever 2¹³. The lever 2¹³ is pivotally mounted at 2¹⁴ and provided at its end with a slot 2¹⁵ with which the lower end of the link rod 2¹² engages. The free end of the lever 2¹³ is secured in its locking position by a swinging link 2¹⁶ which engages the free end of the lever and holds it in its locked position, that is, with the cover 2¹¹ drawn down tight over the upper end of the cylindrical portion 2¹⁰.

4 and 5 indicate cylinders which are secured to the outer casing 1 in proximity to the lower end of the casing 1. The cylinders 4 and 5 extend parallelly at each side of the casing and are each provided at its outer end with orifices 4^x. 6 indicates a pad of resilient material, such as reinforced rubber provided on its inner face with a recess 6^x from which extend a series of orifices 6' such orifices flaring outwardly so as to be distributed equally over the outer face of the pad 6.

7 indicates a pronged member secured to the upper portion of the outer casing 1, the prongs of which are substantially in alignment with the outer face of the pad 6 and are adapted to bear against the side of the vessel to be raised above such pad. 8 indicates a flooring located within the inner casing 2 from which extends a framework, 8^x, 8' and 8² being the members thereof. 9 indicates a motor, which is mounted upon an arched support 9^x carried by the flooring 8. 110 9' indicates the motor shaft extending through the frame member 8² and provided

at its outer end with a pinion 8³. 10 indicates a shaft journaled in the members 8^x, 8' and 8² extending below the motor 9. 10^x indicates a bevel gear suitably splined to the 5 shaft 10 so as to be carried into mesh with the bevel pinion 8³ of the motor shaft 9'. 11 indicates a vertical bearing formed in the flooring 8 beneath the motor 9. 11^x indicates a bearing formed between the flooring 2⁷ 10 and lower end of the inner casing 2. 12 indicates a propeller shaft journaled in the bearings 11 and 11^x, on the lower end of which is mounted a propeller 12^x located in the propeller chamber formed between the flooring 15 2⁷ and lower end of the casing 1. The upper end of the propeller shaft 12 is provided with a bevel gear 12' having an upper and lower beveled face. 13 indicates a shaft mounted at one end in the bearing portion 20 11 and at the opposite end in the frame member 8². 9³ indicates a gear mounted upon the motor shaft 9'. 9⁴ indicates a gear mounted upon the shaft 10 and in mesh with the gear 9³. 9⁵ indicates a gear mounted 25 upon the shaft 13 and in mesh with the gear 9⁴. 13^x indicates a bevel gear suitably splined to the shaft 13 and provided with an annularly grooved hub 13'. 13² indicates an operating lever engaging the hub 13' and 30 pivotally mounted at its upper end at 13². 14 indicates a bevel gear splined to the shaft 10 and provided with an annularly grooved hub 14^x. 14' indicates a bell crank lever pivotally mounted at 14² and engaging 35 the hub 14^x at one end. 13⁴ indicates a link connecting the lever 13² with the upwardly extending arm of the bell crank 14'. 14³ indicates an operating lever, which is pivotally supported upon the lower face of 40 the flooring 8 and connected by a link 14⁴ to the horizontally extending arm of the bell crank lever 14'. 15 indicates a cylinder which is suitably secured to the frame member 8^x and provided 45 at its upper end with ports 15^x and 15' provided with non-return valves 15² and 15³. 15⁴ indicates a tube leading from the port 15^x and extending downwardly through the walls of the inner and outer casing into the 50 water. 15⁵ indicates a tube extending down from the port 15' and provided at its lower end with branches 15⁶ and 15⁷ extending into the cylindrical casings 4 and 5 in proximity to the bottom thereof. 15⁸ indicates a piston 55 operating within the cylinder 15, the piston rod of the piston 15⁸ being connected to an eccentric 15⁹ mounted upon the shaft 10 and by which the piston 15⁸ is given a reciprocating movement. The piston 15⁸ is reciprocated from the motor through the motor 60 shaft 9', bevel pinion 8³, bevel gear 10^x, shaft 10 and eccentric 15⁹ when the bevel gear 10^x is thrown into engagement with the pinion 8³. For this purpose the bevel gear 65 10^x is provided with an annularly grooved

hub 10'. 10² indicates a bell crank lever, the upwardly extending arm of which engages the grooved hub 10', the horizontally extending arm being connected by a link rod 10³ to a bell crank 10⁴ mounted upon the 70 flooring 16 located beneath the flooring 8. The bell crank 10⁴ is connected by a link 10⁵ to an operating lever 10⁶. When the piston 15⁸ is reciprocated the water is drawn from the cylinders 4 and 5 through the branch 75 pipes 15⁶ and 15⁷, tube 15⁵ into the cylinder 15 and is expelled through the tube 15⁴ through the walls of the outer casing into the body of water surrounding the lifting buoy. 80

The propeller 12^x is employed for imparting vertical movement to the lifting buoy, such propeller being driven from the motor through the motor shaft 9', gears 9³, 9⁴ and 9⁵, shaft 13, bevel gear 13^x and lower bevel 85 face of the bevel gear 12' which is carried by the propeller shaft 12.

When it is desired to operate the propeller shaft the lever 14³ is operated, drawing the horizontal arm of the bell crank 14' 90 down and drawing the bevel gear 14 away from engagement with the bevel gear 12' and simultaneously carrying the bevel gear 13^x into engagement with the lower face of the bevel gear 12' by means of the link 13⁴ 95 and lever 13².

When it is desired to reverse the operation the lever 14³ is thrown in the opposite direction carrying the bevel gear 13^x out of engagement with the lower face of the bevel gear 12' and the bevel gear 14 into engagement with the upper face of the bevel gear 12', thus providing for a vertical upward and downward movement.

In order to drive the device horizontally 105 I have provided the propeller 17 mounted upon the propeller shaft 17^x journaled in a bearing 17' formed between the inner and outer casing portions 2^x and 1³. The opposite end of the propeller shaft 17^x is journaled in the frame member 8' and has mounted thereon a bevel gear 17². 17³ indicates a supplemental shaft mounted at one end upon the frame member 8' and at the opposite end in the bearing 17⁴ carried by 110 a suitable portion of the framework. 17⁵ indicates a bevel gear mounted upon the shaft 17³. 17⁶ indicates a bevel gear splined to the shaft 10 and provided with an annularly grooved hub 17⁷. Formed integral 115 with the gear 17⁶ is a bevel pinion 17⁸ having its teeth set in the reverse direction to the teeth of the gear 17⁶. 18 indicates a lever 120 suitably mounted and engaging at its upper end with the groove of the hub 17⁷ and connected at its lower end by a link 17⁹ to a bell crank 17¹⁰ connected by a link 17¹¹ to an operating lever 17¹².

When it is desired to propel the device horizontally in one direction the gears are 130

- set in the position shown in the drawing, that is, with the bevel gear 17³ in engagement with the bevel gear 17⁵. The drive is then carried from the motor 9 through the 5 motor shaft to gear 9³ in mesh with gear 9⁴ mounted upon the shaft 10 and from the shaft 10 to the bevel gear 17⁶, the bevel gear 17⁵, shaft 17³, bevel gear 17⁶ to the gear 17² mounted upon the propeller shaft 17¹.
- 10 When it is desired to propel the device in the opposite direction the operating lever 17¹² is adjusted to carry the bevel pinion 17⁸ into engagement with the bevel gear 17² simultaneously carrying the bevel gears 17⁶ 15 and 17⁵ out of engagement. The drive is then carried from the motor 9 to the shaft 10 in the same manner as above described, the drive being then carried directly from the shaft 10 by the bevel gear 17⁸ to the bevel 20 gear 17² mounted upon the propeller shaft 17¹.
- I will now describe the means whereby an increased buoyancy is given to the device. 18 indicates a cylinder which is mounted 25 in the inner casing above the motor. 18^x indicates a duct leading from the cylinder through the upper wall portions of the outer and inner casings 1 and 2, such duct leading to the atmosphere above the water level.
- 30 The lower end of the duct 18^x is provided with a non-return valve 18¹. 18² indicates a duct also leading from the upper end of the cylinder 18 through the wall of the inner casing 2 so as to feed air into the space 35 formed between the portions of the outer and inner casing. The duct 18² is also provided with a non-return valve 18³. 18⁴ indicates a piston operating within the cylinder 18. 18⁵ indicates a shaft journaled at one 40 end in the frame portion 8² and at the opposite end in a standard 18⁶. 18⁷ indicates a sleeve mounted upon a shaft 18⁵ and on which is mounted an eccentric 18⁸ connected to the piston 18⁴ to impart reciprocating 45 movement thereto. The outer end of the sleeve 18⁷ is provided with a clutch member 18⁹. 18¹⁰ indicates a slidale clutch member operated by a lever 18¹¹ connected by a link 18¹² to a bell crank 18¹³, the opposite arc of 50 which is connected by a link 18¹⁴ to an operating lever 18¹⁵.
- In order to steer the device I provide a rudder 19 which is hingedly mounted upon a vertical shaft 19^x carried by arms 19¹ and 55 19² extending from the outer casing 1 above and below the propeller 17. The lower end of the rod 19^x is provided with a bevel pinion 19⁰. 19³ indicates a shaft journaled in the walls of the inner and outer casings 60 1 and 2. The outer end of the shaft 19^x is provided with a pinion 19⁴ in mesh with the pinion 19⁰. The opposite end of the shaft 19^x is provided with a gear 19⁵ meshing with the gear 19⁶ carried by a shaft 19⁷ journaled 65 at one end in the frame member 8¹ and at the opposite end in the bearing 11. The shaft 19⁷ is also provided with a pulley 19⁸. 19⁹ indicates a shaft journaled in bearings 19¹⁰ carried by the flooring 16. One end of the shaft 19⁹ is provided with an operating 70 lever 19¹¹. The opposite end is provided with a pulley 19¹² connected by a belt 19¹³ to the pulley 19⁸. By manipulating the lever 19¹¹ the rudder 19 may be swung either to one side or the other to carry the device 75 in the direction required.
- In order to provide for necessary ventilation for the interior of my device I have provided cylinders 20 and 21 in which operate pistons 20^x and 21^x, such pistons being 80 reciprocated by eccentrics 20⁰ and 21⁰ mounted upon the shaft 18⁵. 22 indicates a tube connecting the upper end of the cylinder 20 with the air supply duct 18^x. 23 indicates a tube also extending from the upper end of the cylinder 20 and depending down therefrom to a point in proximity to the bottom of the interior casing. By the reciprocation of the piston 20^x air is drawn from the air supply duct 18^x into the cylinder 90 20 and forced down through the tube 23 to the bottom of the casing.
- In order to remove the foul gases from the upper portion of the casing a tube 24 extends from the upper end of the cylinder 21, 95 being open at the top and extending in proximity to the top of the interior casing 2. 25 indicates a tube also extending from the upper end of the cylinder 21 to the atmosphere above the water level. The tubes 24 100 and 25 are provided with non-return valves and the foul air is sucked through the tube 24 into the cylinder and then forced out through the tube 25. By this means thorough ventilation is secured, the fresh air being fed as above described to the lower portion of the interior of the inner casing rises and the foul air collecting at the top of the device is expelled through the tubes 24 and 25. 110
- In operating my device the propeller 12^x is first operated to carry the lifting buoy to the required depth. This propeller is then thrown out of driving connection and the propeller 19 operated to drive the device 115 against the sides of the vessel to be raised which is indicated by the line A—B. The piston 15^x in the cylinder 15 is then operated so as to draw the water out of the cylinders 4 and 5 producing a vacuum therein and 120 thereby carrying the pads 6 into close contact with the side of the vessel, the prong 7 acting as a fulcrum point to draw the lower part of the lifting buoy into the proper position. When this is accomplished the piston 18^x is operated to fill the space formed at the upper portion of the lifting buoy between the outer and inner casings full of air thus 125 rendering the device buoyant and producing a lifting power which will carry the sub- 130

merged vessel to the surface. It will be understood that the number of lifting buoys required to lift the vessel will be regulated by the size of the vessel to be lifted.

5 26 indicate port holes by which the operator can see the location of the lifting buoy in relation to the submerged vessel.

From this description it will be seen that I have devised a very simple device for lifting sunken vessels which may be readily directed by the operator located in the interior of the lifting buoy against the side of the sunken vessel and in which means are provided whereby such operator can attach 10 the device to the vessel and thus render the lifting buoy buoyant in order to lift the sunken vessel to the surface of the water.

15 What I claim as my invention is.

1. A lifting buoy comprising a casing, a pair of horizontally extending cylindrical members carried by the lower portion of the casing, a suction pad carried by the cylinder and having suction orifices communicating

with the interior of the cylinder, and means for exhausting the water from the interior of the cylinder to produce a vacuum therein. 25

2. A lifting buoy comprising a casing having a segmental spherical upper portion and a tapering lower portion, horizontally disposed parallel cylinders carried by the lower portion, a suction pad carried by the end of each cylinder having orifices extending through the pad and communicating with the interior of the cylinder, a suction pump located within the casing of the buoy, tubes 30 extending from the suction pump to the interior of each cylinder, a discharge tube extending from the suction pump through the walls of the casing of the buoy, non-return valves in such tubes, and means located within the interior of the buoy for operating the suction pump. 35
